UNITED STATES PATENT OFFICE

JAMES E. SMITH, OF ROGERSVILLE, MISSOURI

NUTCRACKER

Application filed December 12, 1930. Serial No. 501,932.

This invention relates to new and useful improvements in nut crackers and has for the primary object, the provision of a device of the above stated character which will 5 place a maximum crushing action on a nut with a minimum expenditure of effort on the part of the operator.

Another object of this invention is the provision of movable jaws associated with a 10 base and connected with operating levers whereby one jaw may be actuated by one hand of the operator and the other jaw actuated by a foot of the operator leaving the other hand of the operator free to place 15 and remove nuts from the jaws.

A further object of this invention is the provision of a nut cracker of the above stated character which will be simple, durable and efficient and which may be manufactured and 20 sold at a comparatively low cost.

With these and other objects in view as 25 will become more apparent as the description proceeds the invention consists in certain novel features of construction, combination and arrangement of parts, as will be hereinafter more fully described and claimed.

For a complete understanding of my invention reference is to be had to the following description and accompanying drawings, in which—

Figure 1 is a side elevation illustrating a nut cracker constructed in accordance with my invention.

Figure 2 is an end elevation illustrating 35 the same.

Figure 3 is a perspective view illustrating one of the jaws.

Figure 4 is a similar view illustrating the other jaw.

Figure 5 is a perspective view illustrating a combined support and stop for one of the jaw operating means.

Figure 6 is a perspective view illustrating the lever support.

Figure 7 is a perspective view illustrating a rod shaped element for actuating one of the jaws and carried by the combined support and stop shown in Figure 5.

Referring in detail to the drawings, the 50 numeral 1 indicates a base which may be

bolted or otherwise secured to the table or like support 2 and has mounted thereon a combined support and stop 3 consisting of an elongated member secured to the upper face of the base 1 by bolts 4 and has one end bent 55 to form an upstanding flange 5 terminating in a horizontal flange 6 disposed over a portion of the member 3. The other end of the member 3 is bent and bifurcated to form a pair of relatively spaced attaching arms 7 60 receiving a pivot bolt 8 on which are journalled the pivoted ends of upper and lower jaws 9 and 10, respectively. The jaws 9 and 10 include elongated portions 11 which have one of their ends bent angularly and apertured to receive the pivot bolt 8 while their opposite ends are angularly disposed and of substantially semi-circular shape to provide nut engaging portions 12 and which are concaved or socketed as shown at 13 to receive 65 the ends of the nut 14 as shown in Figure 1 of the drawings.

A wedge-shaped member 15 is slidably mounted on the member 3 and engages under the lower jaw 10 and is limited in its forward movement by the stop defined by the flanges 5 and 6. A pivot pin 16 is carried by the wedge-shaped member 15 intermediate the ends of the latter and has pivotally connected thereto arcuate-shaped arms 17 70 that extend downwardly on each side of the base 1 and are pivotally connected as at 18 to an operating lever 19. The lever 19 is constructed from a single length of material bent intermediate its ends to form a stirrup 20 for 75 the purpose of receiving the foot of the operator, and the parallel portions of the lever are apertured to receive a pivot bolt 21 on the base 1 whereby the movement of the lever 19 in one direction will cause the wedge-shaped member 15 to raise or elevate the lower jaw 10 toward the upper jaw 9.

A substantially U-shaped bracket 22 has its web portion 23 secured to the base 1 by one of the bolts 4 with the member 3 disposed between the arm portions 24 which also have the upper and lower jaws 9 and 10, respectively, disposed therebetween. The free ends of the arm portions 24 are slightly reduced in size and offset inwardly and curved 80 85 90 95 100

laterally to form attaching ears 25 connected by a pivot bolt 26 overlying the upper jaw 9 and on which is journalled a hand lever 27. The lever 27 on the pivoted end thereof is formed with a cam 28 engaging the upper jaw 9. Braces 29 connect the pivot bolts 8 and 26 and have pivotally secured thereto a substantially U-shaped arm 30. The arm portions of the substantially U-shaped arm 30 are bent angularly and have their free ends connected by a bolt 31 which underlies the upper jaw 29 while the web portion of the substantially U-shaped arm 30 is disposed above the upper jaw 9 to be engaged by the hand lever 27 when swung in one direction to cause the arm 30 to rock on its pivot 32 and elevate or move the jaw 9 away from the jaw 10. A movement of the lever 27 in an opposite direction with the nut interposed between the jaws as shown in Figure 1 will cause a downward movement of the upper jaw 9 or in a direction toward the lower jaw 10 by the cam 28 engaging the upper jaw, and a movement of the foot lever 19 in one direction will cause the wedge-shaped member 15 to elevate or move the lower jaw 10 toward the upper jaw 9, thereby efficiently cracking or crushing the shell of the nut 14 and permitting a person to operate the device with one hand and one foot leaving the other foot to stand upon and the other hand to feed nuts to and from the jaws.

While I have shown and described the preferred embodiment of my invention, it will be understood that minor changes in construction, combination and arrangement of parts may be made without departing from the spirit and scope as claimed.

Having thus described my invention what I claim is:

1. A nut cracker comprising a base, a support on said base, jaws pivoted to said support and arranged one above the other and having oppositely disposed nut engaging faces, and hand operating means for one of said jaws, and a foot operating means for the other jaw.

2. A nut cracker comprising a base, a support on said base, upper and lower jaws having one of their ends pivoted to said support and their opposite ends angularly disposed and socketed to provide nut engaging elements, a hand lever for operating one of the jaws, and a foot lever for operating the other jaw.

3. A nut cracker comprising a base, a support on the base, upper and lower jaws pivoted to the support and having nut engaging faces, a jaw operating means slideable on the support and engaging the lower jaw, a foot operating lever connected to the base and said jaw operating member to actuate the respective jaw, and a hand lever for actuating the other jaw.

4. A nut cracker comprising a base, a sup-

port on the base, jaws pivoted to said support to receive a nut, a stop on the support, a wedge-shaped element slideable on the support and engaging one of the jaws, a foot actuated lever pivoted to the base, arms pivoted to the lever and to the wedge-shaped element for actuating said last named jaw, and a hand actuated lever for operating the other jaw.

5. A nut cracker comprising a base, a support on the base, upper and lower jaws pivoted to said support to engage a nut, a foot operating means for actuating the lower jaw, a second support on said base, and a hand operating lever pivoted to the second support and engaging the upper jaw for actuating the latter during the movement of said hand lever.

6. A nut cracker comprising a base, upper and lower jaws pivotally mounted on said base, a foot operating means for the lower jaw, a bracket secured to the base, a hand lever pivoted to said bracket, a cam on the pivoted end of the hand lever to engage the upper jaw for moving said upper jaw toward the lower jaw during movement of the hand lever in one direction, and means associated with the upper jaw to be engaged by the hand lever when moving in one direction for elevating the upper jaw away from the lower jaw.

7. A nut cracker comprising a base, a pivot on said base, upper and lower jaws carried by said pivot, a foot operating means for the lower jaw, a bracket on the base, a hand lever pivoted to said bracket, a cam on said lever for engaging the upper jaw on movement of the hand lever in one direction, braces connecting the pivot to the bracket, an arm pivoted to said braces and engaging under the upper jaw and having a portion disposed in a plane above the upper jaw to be engaged by the hand lever when swung in the opposite direction for elevating the other jaw.

In testimony whereof I affix my signature.

JAMES E. SMITH.
